UNITED STATES PATENT OFFICE.

SAMUEL C. PARKER, OF FARMINGTON, MISSOURI.

WASHING-MACHINE.

SPECIFICATION forming part of Letters Patent No. 339,805, dated April 13, 1886.

Application filed September 7, 1885. Serial No. 176,408. (No model.)

To all whom it may concern:

Be it known that I, SAMUEL C. PARKER, a citizen of the United States, and a resident of Farmington, in the county of St. Francois and State of Missouri, have invented certain new and useful Improvements in Washing-Machines; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved washing-machine. Fig. 2 is a vertical sectional view of the same, taken longitudinally through the roller. Fig. 3 is a vertical sectional view taken on the line *x x* in Fig. 2, and Fig. 4 is a vertical sectional view taken on the line *y y* in Fig. 2.

The same letters refer to the same parts in all the figures.

This invention relates to that class of washing-machines which are constructed with a grooved or fluted cylindrical rubbing-roller adapted to bear with a yielding pressure against a series of smooth rollers, between which and the said fluted or grooved roller the articles to be washed or cleansed will be passed, thus subjecting them to the rubbing action of the rollers.

The invention has for its object to provide a machine of this class which shall possess advantages in point of simplicity, durability, and general efficiency.

With these ends in view the invention consists in the improved construction, arrangement, and combination of parts, which will be hereinafter fully described, and particularly pointed out in the claim.

In the drawings hereto annexed, A designates the frame of my improved machine, which consists, mainly, of the sills B B, bottom piece or base, C, front and rear braces, D D, and the vertical side pieces or uprights, E E. The latter are provided with vertical slots F at their upper ends, and at the upper end of one of the said side pieces is hinged a cross-piece or arm, G, the free end of which is secured in the upper end of the slot F of the other side piece by means of the transverse pin H. The cross-piece or arm G may serve

as a handle by which the machine may be grasped and held securely while it is in operation; but when, as is sometimes the case, the 55 said arm or cross-piece shall be thought to interfere with the operation of the machine, in obstructing the free manipulation of the clothes, the pin H may be removed, and the arm or cross-piece G may then be thrown back 60 and out of the way, as will be seen in dotted lines in Fig. 1 of the drawings hereto annexed.

Secured to the inner sides of the side pieces or uprights, E E, of the frame are the brackets 65 I I, having laterally-extending arms J J, and provided in their under edges with vertical slots K, forming bearings for the main roller-shaft L. One end of said shaft should project a sufficient distance to extend over the 70 edge of a tub in which the machine may be placed for operation, and the said projecting end is to be provided with a crank, M, by means of which it may be conveniently turned or manipulated. The shaft L carries the 75 grooved or fluted roller N, which may be constructed of hard wood, or of any other suitable material.

O O designate a pair of vertically-sliding blocks or boxes arranged between the front 80 and rear braces, D D, adjoining the inner sides of the uprights E E, and provided with laterally-extending arms P P, which are connected with the arms J J of the brackets I I by means of coiled springs Q Q, which tend 85 to force the said blocks or boxes in an upward direction toward the blocks or brackets I I. The blocks or boxes O O are fitted loosely between the front and rear sides, D D, of the frame, so that they may have a vibrating motion. The lower portion of said boxes, the ends 90 of which are formed square, will serve to prevent the said boxes and brackets from working out of the frame while the machine is in operation, as the said square ends will bear 95 against the braces D D, and thus retain them in the frame, and the said boxes form bearings for the ends of a series of smooth rollers R R, arranged segmentally and adapted to bear against the periphery of the grooved or fluted 100 roller N, with which they are held in contact by the action of the springs Q Q.

The ends of the frame A are provided with pivoted hooks S S, adapted to engage suitable

staples in the rim of the tub or suds box in which my improved washing-machine is placed for operation.

From the foregoing description, taken in connection with the drawings hereto annexed, the operation and advantages of this invention will be readily understood. The general construction is simple and inexpensive, and the machine is durable and efficient. The clothes being inserted between the smooth and the fluted rollers, and the shaft of the latter being rotated, the clothes will be passed back and forth, and will be meanwhile subjected to friction and pressure, which will be efficient in removing the dirt.

Having thus described my invention, I claim and desire to secure by Letters Patent of the United States—

The combination of the frame A, having up-

rights E, slotted at their upper ends, brackets I, having laterally-extending arms J, the lower portion of each of said brackets being provided with a slot, K, blocks O, having laterally-extending arms P, springs connecting the arms of said brackets and blocks, a fluted roller, N, journaled in the said brackets, a series of segmentally-arranged rollers, R, journaled in the said blocks, and a crank, M, for operating the said fluted roller, substantially as shown and described.

In testimony that I claim the foregoing as my own I have hereunto affixed my signature in presence of two witnesses.

SAMUEL C. PARKER.
